UNITED STATES PATENT OFFICE.

CARL HAMBURCHEN, OF BELLEVILLE, ILLINOIS, ASSIGNED TO AMERICAN CARBON & BATTERY CO., OF EAST ST. LOUIS, ILLINOIS, A CORPORATION OF ILLINOIS.

HAND-LAMP.

1,223,369.

Specification of Letters Patent. Patented Apr. 24, 1917.

Application filed September 30, 1916. Serial No. 122,921.

To all whom it may concern:

Be it known that I, CARL HAMBURCHEN, a citizen of the United States, residing at Belleville, county of St. Clair, and State of Illinois, have invented certain new and useful Improvements in Hand-Lamps; and I do hereby declare the following to be a full, clear, and exact description of the invention, such as will enable others skilled in the art to which it appertains to make and use the same.

It is an object of the present invention to provide a battery hand lamp having improved means for making and breaking the electrical connection between the battery and the lamp, and more particularly to provide a construction wherein the battery is protected from inadvertent short-circuit through the case or parts thereof, and wherein the lamp is protected from inadvertent lighting, as by accidental shifting of the thumb piece whereby the hand lamp is normally controlled.

To effect those objects and others herein-after pointed out, or which are inherent in the construction of the device, the conductors from one terminal of the battery are completely housed by insulating material and thereby the battery is protected against the accidental flow of current through bridging of exposed metal parts, as when the lamp is carried among metal tools, and, furthermore, the switch mechanism for the lamp includes, in addition to the main thumb-controlled switch, an auxiliary contact device whereby the circuit connections may be opened at a second point and locked open, thereby keeping the battery and lamp inactive irrespective of manipulations of the thumb piece.

In the accompanying drawings:—

Figure 1 is a plan view of the complete battery hand lamp.

Fig. 2 is a sectional elevation of the same.

Fig. 3 is an end elevation showing the inside of the cap or base with which the casing is provided.

Fig. 4 illustrates one of the contact members near the base of the tubular casing.

Fig. 5 is a fragmentary elevation on the line 5—5 of Fig. 3, illustrating the spring used to lock the cap against accidental turning.

Fig. 6 is a punching whereby the coil spring is secured to the end-cap of Fig. 3.

Fig. 7 illustrates a modified form of contact ring.

Fig. 8 is a fragmentary longitudinal section of an embodiment wherein the tubular casing is of metal instead of fiber or the like.

In the embodiment illustrated in Figs. 1 to 7, inclusive, the battery hand lamp comprises a tubular casing 1 of hard fiber or other suitable insulating material, and has threaded metal ends provided by threaded sheet metal sleeves 2 and 3 riveted or otherwise suitably secured to the fiber tube. At the front end of tube 1 is a threaded collar 4 engaging sleeve 2 and serving to clamp lens 5 and the outturned edge of reflector 6 against the front end of the casing, where the edge of the fiber insulation is overlapped by an inturned flange on sleeve 2. A lamp 7 is threaded into the reflector in usual manner and the inner lamp terminal contacts with the inner or top electrode 8 of a battery 9 comprising a plurality of cells arranged end to end within a cardboard tube 10. The bottom of the lowermost cell is exposed for contact with a coil spring 11 at the base of the lamp and carried by and insulated from a metal cap 12 which has threaded engagement with sleeve 3.

The switch mechanism for the battery hand lamp comprises conductor 13, preferably in the form of a strip of metal, underlying the flange on sleeve 2, and so establishing connection with one lamp terminal through reflector 6. This strip 13 is riveted or otherwise secured to a metal plate 14 riveted to the outside of casing 1. Over this plate slides a thumb piece 15 to which is secured by rivets passed through slots in plate 14 a sliding contact finger 16, preferably in the form of a metal strip, which extends downward between the battery and the casing and terminates within or near cap 12. It is by this thumb piece 15 and its sliding contact finger 16 that the lighting of lamp 7 from battery 9 is ordinarily controlled.

Secured to the tubular wall of casing 1 and insulated thereby, and lying in the path of the sliding contact finger 16, is a contact member 17 in the form of a metal ring. Adjacent this ring, and adapted to move into and out of electrical connection therewith, is a second contact member 18 in the form of a metal plate or punching (Fig. 6), having integral loops 19 under which the

lowermost turn of spring 11 is gripped to hold that spring in position and secure electrical connection therewith and having integral tangs 20 which are passed through slots in an insulating disk 21 of fiber, or the like, and there clenched down between that disk and a second imperforate fiber disk 22, whereby metal cap 12 is lined and insulated from the tangs.

10 Plate 18 has its ends swaged to yieldingly engage and establish electrical connection with ring 17 when cap 12 is screwed up tight on collar 3, but the plate moves out of engagement with ring 17 when the cap is unscrewed a turn or two, and these parts therefore constitute a switch mechanism whereby the circuit from the battery to the lamp may be interrupted irrespective of the position of thumb piece 15, whereby 15 the other or primary switch mechanism of the lamp is controlled to switch the lamp on or off as desired.

In order that cap 12, after being partly unscrewed from sleeve 3, may not accidentally come off entirely, or be accidentally screwed up again far enough to establish contact between plate 18 and ring 17, and particularly that the user may know when the cap has been unscrewed far enough to open the auxiliary switch mechanism and render thumb piece 15 ineffective for lighting the lamp even accidentally, there is provided a spring finger 23 of metal riveted to disk 21 and having its free 30 yielding end projecting outward for engagement with a recess in ring 17. This recess may be in the form of a notch 24 (Fig. 7) cut in the bottom edge of the ring, or may be a notch or indentation 25 (Fig. 4) on the 35 inner face of the ring. In either case the spring and recess are so positioned that after cap 12 has been unscrewed far enough to open the auxiliary switch mechanism, spring finger 23 will enter the recess of ring 40 17, thereby forming in effect a lock to prevent accidental rotation of the cap either forward or backward. With the auxiliary contact mechanism thereby locked in open position, the battery hand lamp may be subjected to rough usage and carried about in 45 a tool kit and in contact with metal tools without danger of lighting the lamp and wasting the battery energy through inadvertent shifting of thumb piece 15, and 50 without danger of short-circuiting the battery on itself or through the lamp, because of contact of these metal tools with exposed metal parts of the construction.

In the modification illustrated in Fig. 8, 55 the tubular casing 26, wherein the batteries are housed, is of metal having at its ends threads 27 pressed therein to serve in place of the sleeves 2 and 3 of Fig. 1. The thumb piece 28 may in this modification slide directly on metal tube 26 through which con-

nection is established to the lamp by way of the reflector, as will be understood, but other features of this modification, including the sliding contact finger 29, the insulated contact ring member 30, and the other 70 co-operative parts, are the same as illustrated in Fig. 2 and described above.

I claim:—

1. In a battery hand lamp, the combination of a tubular casing, a battery therein 75 comprising a plurality of dry cells arranged end to end, a lamp having one terminal connected with said battery, connections between the other terminal of said lamp and said battery, said connections including two 80 switch mechanisms arranged in series, either of which may be operated to interrupt the flow of current from said battery to said lamp one of said switch mechanisms having an actuating thumb-piece on the side of 85 said tubular casing and the other having a lock to hold it in open position.

2. In a battery hand lamp, the combination of a casing, a battery therein, a lamp to be supplied with current from said battery, a thumb-piece on said casing, switch mechanism between said battery and said lamp and comprising a finger within said casing and extending longitudinally thereof, 90 said finger being movable by said thumb-piece to open the circuit to the lamp, and means for opening the battery circuit at another point when desired to prevent accidental lighting of the lamp by inadvertent movement of said thumb-piece. 95

3. In a battery hand lamp, the combination of a tubular casing, a battery therein comprising a plurality of dry cells arranged end to end, a lamp having one terminal contacting with a battery terminal, and switch 105 mechanism for connecting the other lamp terminal to the remaining battery terminal, said mechanism comprising a contact finger and two contact members, said contact finger being normally connected with a lamp 110 terminal and extending and moving longitudinally of said casing, said finger and one of said members being movable into engagement with the other contact member to complete the circuit from the battery to the 115 lamp.

4. In a battery hand lamp, the combination of a tubular casing, a cap secured to one end of said casing, a collar secured to the other end thereof, a lens and a reflector clamped between said collar and the adjacent casing end, a lamp threaded into said reflector, a battery within said casing and having one terminal connected with the inner terminal of said lamp, and switch mechanism between the other terminal of said battery and said reflector, said mechanism comprising a thumb-piece movable on said casing, a contact finger electrically connected with said reflector and movable with 120 125

said thumb-piece and extending longitudinally of said casing, an insulated contact member in the form of a ring with which said finger may engage to complete the circuit to the lamp, a second contact member in the form of a yielding plate housed within said cap and movable to make or break contact with said contact ring member, and a spring connecting said contacting plate with the bottom of the battery.

5. In a battery hand lamp, the combination of a tubular casing, a cap secured to one end of said casing, a collar secured to the other end thereof, a lens and a reflector clamped between said collar and the adjacent casing end, a lamp threaded into said reflector, a battery within said casing and having one terminal connected with the inner terminal of said lamp, and switch mechanism between the other terminal of said battery and said reflector, said mechanism comprising a thumb-piece movable on said casing, a contact finger electrically connected with said reflector and movable with said thumb-piece and extending longitudinally of said casing, an insulated contact member in the form of a ring with which said finger may engage to complete the circuit to the lamp, a second contact member in the form of a yielding plate housed within said cap and movable to make or break contact with said contact ring member, a spring connecting said contacting plate with the bottom of the battery, and a lock to hold said cap against accidental turning when said contact members have been separated.

6. In a battery hand lamp, the combination of a tubular casing of insulating material, a metal sleeve on each end thereof, a metal cap secured to one of said sleeves, a collar secured to the other of said sleeves, a lens and a reflector clamped between said collar and its sleeve, a lamp threaded into said reflector, a battery within said casing and having one terminal connected with the inner terminal of said lamp, and switch mechanism between the other terminal of said battery and said reflector, said mechanism comprising a conductor connected with said reflector, a plate mounted on said tubular casing and connected with said conductor, a thumb-piece mounted on said plate, a contact finger movable with said thumb-piece and extending longitudinally of said casing, an insulated contact member in the form of a ring with which said finger may engage to complete the circuit to the lamp, a second contact member in the form of a yielding plate housed within said metal cap and movable therewith to make or break contact with said contact ring member, insulating means whereon said contact plate is secured, a spring held by said contact plate and engaging the bottom of the battery, and a lock to hold said cap against accidental

turning when said contact members have been separated to prevent accidental lighting of the lamp.

7. In a battery hand lamp, the combination of a tubular casing having threaded metal ends, a metal cap threaded to one of said ends, a collar threaded to the other of said ends, a lens and reflector clamped between said collar and its threaded end, a lamp threaded into said reflector, a battery within said casing and having one terminal connected with the inner terminal of said lamp, and switch mechanism between the other terminal of said battery and said reflector, said mechanism comprising a thumb-piece slidingly mounted on said casing, a contact finger movable with said thumb-piece and extending longitudinally of said casing, an insulated contact member in the form of a ring with which said finger may engage to complete the circuit to the lamp, a second contact member in the form of a yielding plate housed within said threaded metal cap and movable therewith to make or break contact with said contact ring member, an insulating disk whereon said contact plate is secured, a coiled spring held by said contact plate and engaging the bottom of the battery, and a lock to hold said cap against accidental turning when said contact members have been separated to prevent accidental lighting of the lamp.

8. In a battery hand lamp, the combination of a tubular casing of insulating material, a threaded metal sleeve on each end thereof, a metal cap threaded to one of said sleeves, a collar threaded to the other of said sleeves, a lens and a reflector clamped between said collar and its sleeve, a lamp threaded into said reflector, a battery within said casing and having one terminal connected with the inner terminal of said lamp, and switch mechanism between the other terminal of said battery and said reflector, said mechanism comprising a conducting strip contacting with said reflector, a plate mounted on said tubular casing about midway of its length and connected with said strip, a thumb-piece slidingly mounted on said plate, a contact finger movable with said thumb-piece and extending longitudinally of said casing, an insulated contact member in the form of a ring with which said finger may engage, a second contact member in the form of a yielding plate housed within said threaded metal cap and movable therewith to make or break contact with said contact ring member, an insulating disk whereon said contact plate is secured, a coiled spring held by said contact plate, and a lock to hold said cap against accidental turning when said contact members have been separated to prevent accidental lighting of the lamp.

9. In a battery hand lamp, the combina-

tion of a tubular casing having a threaded metal end, a metal cap threaded to one of said ends, a collar threaded to the other of said ends, a lens and a reflector clamped between said collar and its threaded end, a lamp threaded into said reflector, a battery within said casing and having one terminal contacting with the inner terminal of said lamp, and switch mechanism between the 10 other terminal of said battery and said reflector, said mechanism comprising a thumb-piece slidably mounted on said tubular casing and electrically connected with said reflector, a contact finger movable with said 15 thumb-piece and extending longitudinally of and within said casing, an insulated contact member in the form of a ring with which said finger may engage, a second contact member in the form of a yielding plate housed within said threaded metal cap and 20 movable therewith to make or break contact with said contact ring member, an insulating disk whereon said contact member is secured, a coiled spring held by said contact plate in integral loops thereof and a 25 spring blade carried by said disk, said ring member having a notch to receive said blade and form therewith a lock to hold said cap against accidental turning when said contact 30 members have been separated to prevent accidental lighting of the lamp.

10. In a battery hand lamp, the combination of a tubular casing of insulating material, a threaded metal sleeve on each end thereof, a metal cap threaded to one of said 35

sleeves, a collar threaded to the other of said sleeves, a lens and a reflector clamped between said collar and its sleeve, a lamp threaded into said reflector, a battery within said casing and having one terminal contacting with the inner terminal of said lamp, and switch mechanism between the 40 other terminal of said battery and said reflector, said mechanism comprising a conducting strip contacting with said reflector, a slotted plate mounted on said tubular casing about midway of its length and connected to said strip, a thumb-piece slidably mounted on said plate, a contact finger movable with said thumb-piece and extending longitudinally of and within said casing, an insulated contact member in the form of a ring with which said finger may engage, a second contact member in the form of a yielding plate housed within said threaded metal cap and 45 movable therewith to make or break contact with said contact ring member, an insulating disk whereon said contact plate is secured by integral tangs, a second insulating disk between said tangs and said metal cap, a coiled spring held by said contact plate in integral loops, and a spring blade carried by said first-named disk, said ring member having a notch to receive said blade and form a lock to hold said cap against 50 accidental turning when said contact members have been separated to prevent accidental lighting of the lamp.

In testimony whereof I affix my signature.
CARL HAMBUECHEN.
